DUPLICATING MACHINE

Edgar M. McNabb, Indianapolis, Ind.

Application August 5, 1952, Serial No. 302,747

9 Claims. (Cl. 282—15)

1

The invention described herein relates to a register wherein a plurality of forms are brought into a superimposed relationship from any suitable supply source, such as from individual rollers or from a fanfold pack to have carbon paper interleaved therebetween, particularly to have that carbon paper brought between upper and lower forms to have free ends of the carbon paper directed in the direction of travel of the forms through the register, and wherein those carbon sheets are intermittently fed to travel in the same direction as that of the superimposed forms, but to travel at much less distance than is the travel of each individual form.

The invention further involves the feeding of another form transversely of the direction of the primary forms, and utilizing a carbon sheet fed along with the primary forms, with the further operation of cutting off this secondary, transversely fed form into lengths upon, for example, a one line entry on the superimposed forms.

Furthermore, the invention resides in the various combinations of elements in their new associations as set forth by the appended claims.

The invention is described in one particular form as now best known to me in reference to the accompanying drawings, in which

Fig. 1 is a view in side elevation of a structure embodying the invention with portions of the housing and cover broken away;

Fig. 2 is a top plan view of the structure with a portion of the cover broken away;

Fig. 3 is a transverse vertical section on the line 3—3 in Fig. 2 through a carbon paper roll;

Fig. 4 is a view in section on the line 4—4 in Fig. 3;

Fig. 5 is a view on an enlarged scale in top plan of the table portion of the register with the cover removed;

Fig. 6 is a view in transverse vertical section on the line 6—6 in Fig. 2, on an enlarged scale;

Fig. 7 is a detail in side elevation on an enlarged scale of the transversely fed paper cutter;

Fig. 8 is a view in transverse section on the line 8—8 in Fig. 1;

Fig. 9 is a detail on an enlarged scale in vertical section on the line 9—9 in Fig. 8; and

Fig. 10 is a detail on an enlarged scale in section on the line 10—10 in Fig. 9.

The structure is primarily supported upon two spaced apart longitudinally extending angle irons 15 and 16. A pair of rear columns 17 and 18 and a front plate 19 support therebetween a table 21 which has side guides 22 and 23 between which forms 24 are guided in straight line directions

2

longitudinally of travel across the table 21. A housing 25 surrounds the entire mechanism, and has an upper cover 26 closing the upper side thereof with the exception of a window 27 at the forward end portion of the table 21.

While the device may use any desired multiple number of forms 24, that is in duplicate, triplicate, quadruplicate and the like, the device is illustrated as having three such forms fed therethrough, the forms being therefore in triplicate.

As illustrated in Fig. 1, the three sets of forms, 24, 24a, and 24b are in a fanfold pack carried preferably in a drawer 28 in the extreme rear end of the housing 25. The drawer slides between the angle irons 15 and 16, to be easily removable for refilling with the pack.

Where a separate line by line impression is to be taken at the same time entries are made on the primary forms 24, 24a, and 24b, such as for

20 the purpose of stock control for inventory systems, and for shipping directions, there is provided a supply of paper either in fan-fold or roll form, herein shown as a roll of tape 29 revolvably supported on the side of the device, Figs. 6 and 8,

25 to have the tape carried upwardly under a friction holding finger 30 and on up and over transversely across the top side of the table 21 between feed rollers 31 and 32 on the left hand upper side of the device. From between the rollers 31 and 32, the tape 29 is carried downwardly under a stationary shear bar 33 and over a retaining lip 134 and outwardly through the side of the housing 25.

Where the forms are to be utilized in triplicate, 35 and the tape 29 is employed, there are three rolls of carbon paper 34, 35, and 36 employed. Each of these carbon paper rolls has its paper wound about a core or spool 37, hollow to receive therethrough a spindle 38, Figs. 3 and 4. This spindle

40 38 has on its right hand side a circular plate 39 from which extends a tubular sleeve 40 telescoping over the spindle 38 to terminate by an end to abut the end of the spool 37 for aligning the right hand edge of the carbon paper in respect to its presentation over the table 21. In

45 order to retain the spool 37 in fixed longitudinal position along the spindle 38 there are provided a plurality of spring fingers 41, herein shown as three in number, Fig. 4, to have ends turned downwardly into a groove 42 around the spindle 38, and extend therefrom over the spindle 38 and within the thimble 40 into the inside of the spool 37 to grip the inside wall thereof frictionally. At the other end of the spool 37 there is inserted 50 a ferrule 43 to enter into the end of the spool

37 in order to centrally align that spool with the axis of the spindle 38.

Extending rearwardly from the rear posts 15 and 16 are vertically disposed plates 44 and 45, as means for supporting the three carbon paper rolls. The plate 44 carries, fixed thereto, a thimble 46, Fig. 3, to extend inwardly from the plate 44 and to have a plate 47 fixed thereto, through which there is an opening into the tube 46 to permit the end 48 of the spindle 38 to enter revolvably therein. The spindle plate 39 carries thereon a friction breaking member 49 to be compressed between the plate 39 and the plate 47.

The other end of the spindle 38 passes freely through the plate 45 to have its end 50 entered into a socket 51 carried by a spring tongue 52 in turn secured to the plate 45 whereby the tongue 52 can yieldingly urge the spindle 38 longitudinally toward the plate 47 to effect the compressive engagement of the friction material 49 with the plate 47 so as to frictionally resist rotation of the spindle 38. Each of the other rolls 35 and 36 are mounted in exactly the same manner.

Carbon paper from the roll 34 is pulled across the table 21 to overlay the tape 29. Form 24b is brought up over the rear side of the carbon paper roll 34 preferably over a bar 53 between the rolls 34 and 35, and carried forwardly over the carbon paper 34 across the table 21. Then the next form 24a is brought up over the cross bar 54 to have carbon paper from the roll 35 carried along with and under that form 24a so as to have both the carbon paper and the form 24a overlap the first form 24b. Then the carbon paper from the roll 36 is carried over the top of the form 24a across the table 21, and finally the form 24 is brought over the carbon paper 36.

The carbon paper as indicated in Fig. 2 has a width less than the spacing between the form guides 22 and 23, therefore being less in width than the width of the forms 24. In other words, the carbon papers 34, 35 and 36 do not come into contact with these guides 22 and 23 and are at no time guided thereby. To the contrary, all three sets of the forms 24 are guided between these guides 22 and 23 in their passage across the table. The top form 24 as described as coming over the carbon paper 36 is supported from direct drag on the roll of that paper by means of a transverse rounded plate 55.

At the front end of the table 21, there are a pair of upright posts 56 and 57, herein shown as constituting upturned legs from a transverse bar 58 secured to the angle irons 15 and 16, Fig. 8. These posts 56 and 57 serve as supports for the transverse shaft 59 and for an upper presser roller shaft 60.

Fixed to the shaft 59, and inside of the posts 56 and 57, are two paper form feed rolls 61 and 62. These rolls 61 and 62 are spaced apart on the shaft 59 that distance which will permit the peripheries of those rollers to lie immediately under the extreme marginal edge portions respectively of the form 24, that is those edge portions which are adjacent the guides 22 and 23. The top sides of the peripheries of the rollers 61 and 62 are substantially in the plane of the top side of the table 21. The carbon papers 34, 35, and 36 will pass between these rollers 61 and 62 without contact in any respect therewith. Each set of forms 24, 24a, and 24b is provided with punchings, elliptical in shape longitudinally of the direction of travel of the forms, indicated by the numerals 63 and 64, these punchings being located near the top edge of the respective

forms as defined by the perforated line 65, Fig. 5. These punchings 63 and 64 are immediately adjacent the respective side edges of the forms. These punchings 63, 64 furthermore will pass over the peripheral portions of the rollers 61 and 62.

The upper transverse shaft 60 carries the respective rollers 66 and 67 in vertical alignment with the rollers 61 and 62 thereunder. This shaft 60 is compressively urged toward the shaft 59 by means of compression springs, Fig. 9, 68, one in each of the posts 56 and 57 carried downwardly against the shaft 60 by means of the adjusting screws 69. Normally, in the absence of any forms therebetween, these rollers 66 and 67 would be compressively urged into rolling contact with the rollers 61 and 62 thereunder. The forms 24, 24a, and 24b when initially fed across the table 21 have their forward ends, that is their normally upwardly disposed ends, placed between the rollers 66, 61 and 67, 62, to bring the forms or rulings on the forms into proper alignment as viewed through the window 27.

The rollers 61 and 62 are provided with lobes 25 or cams 70 and 71 respectively which are spaced to come up against the roller 66 and 67 outside of the side edges of the forms 24, Fig. 5. These cams 70 and 71 serve to lift the rollers 66 and 67 from compressive contact against the forms, so that the forms may be freely pulled between the rollers 66, 61 and 67, 62, that is in non-feeding relation. Normally the pressure of the upper rollers 66 and 67 against the under rollers 61 and 62 is sufficient to carry all of the forms therebetween and over the table 21, it being expressly understood that the carbon papers 34, 35, and 36 remain stationary in respect to longitudinal travel and are not fed along with these forms by means of the rollers 66 and 67.

Each roller 61 and 62, Fig. 9, carries a finger 72 to extend normally beyond the periphery of not only the roller itself, but also the periphery of the cams 70 and 71. The finger 72 is fixed on a rockably mounted pin 73 to which is fixed an arm 74. A tension spring 75 interconnects this arm 74 with a fixed abutment 76 carried by the roller 62 as indicated in Fig. 9. The spring 75 therefore tends to maintain yieldingly the finger 72 in its outermost position. The shaft 59 is provided with a crank 76 externally of the housing 25 as a means of rotating the shaft. By turning the crank 76, the fingers 72 are brought around to enter the punchings 63 and 64, these fingers being turned uppermost when the forms are originally positioned on the table 21 for feed alignment. In other words, the forms are aligned one over the other to have the punchings 63 and 64 in the respective forms in alignment and to have the fingers 72 extending therethrough.

Then the crank 76 is turned to carry the forms forwardly and to carry the cams 70 and 71 on around to allow the rollers 66 and 67 to come down into their normal compressive engagement against the forms to grip them between those rollers 66 and 67 and the rollers 61 and 62 for normal feeding of the forms. As the fingers 72 come around, they will contact the rollers 66 and 67, and by reason of the spring 75 in each instance, those fingers 72 will yieldingly retract and rock relatively rearwardly to relieve those fingers from engagement through the punchings 63 and 64 to permit the forms to travel on past the fingers.

To cooperate with those fingers 72, there is a rocker plate 77 provided to be pivotally engaged

by its outer ends through the pins 78 and 79 with upper end portions of the posts 56 and 57. The rocker plate 77 is cut away to form a boundary around the sides and the upper portion of the window 27. The plate 77 consists essentially of two side fingers 80 and 81 extending down along the marginal side portions of the forms, to be interconnected by a forward transverse portion 82. The fingers 80 and 81 are each provided with slots 83 and 84 in alignment with the punchings 63 and 64 so that the forms 24 are held downwardly against the plate 21 when the fingers 72 come up through those punchings and effect a longitudinal movement into alignment of the three forms, the fingers 80 and 81 bearing just enough to prevent lifting of the papers, and yet permitting those papers to be easily separately moved by the fingers 72 to effect longitudinal movement into alignment of the three different forms.

In other words, upon each complete revolution of the crank 76, and corresponding one complete revolution of the rollers 61 and 62, the three forms are inter-aligned one with the other by means of these fingers 72. The circumferential lengths of the peripheries of these rollers 61 and 62 correspond to the overall feed length for one individual length of form 24.

The transverse tape 29 is fed by travel of the rollers 31, 32. One of these rollers, roller 32, is driven by means of a flexible shaft 85 directly connected to a spur gear 86 which is in constant mesh with a drive gear 87 mounted on a transverse shaft 88. This shaft 88 extends outwardly through the housing 25 on the same side as is mounted the crank 76, and the shaft 88 carries on this outer end a crank 89. A second spur gear 90 is in constant mesh with the gear 87, and this spur gear 90 is fixed on a transverse shaft 91 which extends across to the opposite side of the device, to carry in fixed relation thereon a cam 92.

A knife 93 is rockably mounted on a pivot bolt 94 on the side of the bar 33, to be swingable across the under edge of the bar 33 in a shear action, the bar 93 swinging upwardly to effect a shear cut of the tape 29 which extends between the under side of the bar 33 and over the lip 134. The knife 93 has a rear heel portion 95 extending past the pivot bolt 94 to be in the path of the cam 92, so that as the shaft 91 revolves in the direction of the arrow, clockwise as viewed in Fig. 7, the knife 93 will be rocked downwardly. An arm 96 extends downwardly from the junction of the knife 93 and the arm 95 centrally of the pivot axis through the bolt 94 to have springs 97 and 98 respectively interconnect its lower end to extend forwardly and rearwardly to fixed posts 99 and 100 so that the knife 93 will be returned to its position as indicated in Fig. 7, which is the position out of the way of the feed of the tape across the lip 134. When the cam 92 revolves, it will pull the knife 93 down in opposition to the spring 97, which spring will in turn kick the knife 93 upwardly in a snap action when the cam 92 has traveled beyond the foot 95, and the spring 98 serves to return the knife 93 to its down position. These two springs 97 and 98 balance and pull when the knife 93 is positioned as indicated in solid lines.

Turning of the crank 89 also controls the line by line feed of the forms 24 after the forms 24 have been initially aligned by the fingers 72 in the manner above described. On the shaft 88 there is mounted an eccentric 101 around which is

a strap 102. Fixed to the strap 102 is a pawl 103 extending forwardly to drop by its forward end into the path of a ratchet wheel 104 mounted on the shaft 59 outside of the post 56. Further, this ratchet wheel 104 is mounted outside of the spur gear 105 which is also fixed to the shaft 59 and is in constant mesh with the pinion gear 106 fixed to the upper presser roller shaft 60 so that the presser rollers 66 and 67 are positively driven along with the rollers 61 and 62 when the crank 76 is turned, or when the shaft 59 is turned. A spring 107 normally and yieldingly holds the forward end of the pawl 103 down against the teeth of the wheel 104. Thus, upon each turn of the crank 89, the pawl 103 is reciprocated fore and aft to engage with a predetermined number of teeth on the ratchet wheel 104 depending upon the throw of the eccentric 101. One particular setting would be for the shaft 59 to advance the forms 24 one full line at a time. In other words, after one line of the form is written upon through the window 27, the turning of the crank 89 one complete revolution will advance the forms the distance between adjacent cross rulings so that only one line at a time of the form 24 is presented for writing thereon. This line will be immediately above the tape 29 thereunder and lying against the table 21.

When the form 24 has been filled out as far as it is intended to be filled, then the crank 89 is no longer turned, to give exposure of the form 24 one line at a time through the window 21, but the crank 76 is then turned to carry the forms on out to have the perforated line 65 come under the tear off lip 108.

So far there has been no feed longitudinally of the table 21 of the carbon papers 34, 35 and 36. These carbon papers are fed only a distance once each complete revolution of the crank 76. Even then, the carbon papers are fed only a relatively short distance, preferably not exceeding the spacing apart of the transverse ruled lines on the form 24.

This feeding of the carbon papers is effected as follows: There is a roller 110 mounted substantially centrally of the length of the shaft 60 between the rollers 66 and 67. The forms 24 pass under this roller 110. On the shaft 59 there is a cam, herein shown as a pin 111, to be in the path of an arm 112 which is rockably mounted to swing vertically under the level of the table 21. This arm 112, which is herein shown as being pivoted on the pin 113 through a bracket 114 which extends downwardly from under the table 21 and rearwardly of the shaft 59, to have the arm 112 normally positioned to incline forwardly and downwardly over the shaft 59.

From the arm 112, there is carried a leaf spring 115 to extend forwardly and thence around through a loop 116 rearwardly by a length 117 to terminate in an up and forwardly directed leg 118. This leg 118 is so positioned that when the pin 111 is brought against the under side of the arm 112, it will come upwardly to press through an opening 119 in the table 21 against the stack of carbon papers and forms lying on the table 21 and under the roller 110 to make a like compressive contact against that stack compressing it against the roller 110 for momentary compression as long as the pin 111 maintains the arm 112 in the elevated position as indicated in Fig. 9. Now this contact of the leg 118 with the stack of papers can be made at any time as long as the rollers 66 and 67 are in compressive con-

tact against the forms holding them against the rollers 61 and 62 for feed through the device.

During this momentary compressive contact against the stack of papers, the carbon papers 34, 35 and 36 are gripped against and between the forms to be pulled along therewith during that contact, the removal of the contact causing the cessation of feed of the carbon papers. In other words, during a small portion of travel of the crank 16, the carbon papers are fed forwardly in order to bring the papers into new alignment with the various lines across the forms in order that clear impressions may be made.

The thicknesses of the forms and of the carbon papers are grossly exaggerated in Figs. 6 and 9, but are purposely exaggerated in order to distinguish the various sheets. As indicated in Fig. 9, the uppermost forms 24 and 24a are brought around under the tear off lip 108 externally of the housing 25, while the other form 24b is fed downwardly through an opening 120 through the top side of the housing 25 so that one carbon copy may be retained within a forward compartment 121 provided in the housing. Of course, all three sets of the forms may be pulled directly outwardly under the lip 108 if so desired.

In any event, while I have herein shown and described my invention in the one particular form, it is obvious that structural variations may be made without departing from the spirit of the invention, and I therefore do not desire to be limited to that precise form beyond the limitations which may be imposed by the following claims.

I claim:

1. In a duplicating machine employing multiple strips of forms and carbon paper strips entered between the strips with widths less than the widths of the form strips; the structure for advancing the carbon strips from rolls to have free ends of the carbon strips between the strips presented in the direction of travel of form strip advancement which comprises means for gripping the marginal side edges of said form strips only beyond the side edges of the carbon paper strips and pulling the form strips for a predetermined distance to allow the form strips to slide over said carbon paper strips remaining stationary; and means squeezing together said form and carbon paper strips for an interval of time during said pulling to cause said carbon paper strips to drag along with the form strips during that interval only.

2. In a duplicating machine employing multiple strips of forms and carbon paper strips entered between the strips with widths less than the widths of the form strips; the structure for advancing the carbon strips from rolls to have free ends of the carbon strips between the strips presented in the direction of travel of form strip advancement which comprises means for gripping the marginal side edges of said form strips only beyond the side edges of the carbon paper strips and pulling the form strips for a predetermined distance to allow the form strips to slide over said carbon paper strips remaining stationary; and means squeezing together said form and carbon paper strips for an interval of time during said pulling to cause said carbon paper strips to drag along with the form strips during that interval only; and means yieldingly tensioning said carbon paper strips to retain it in said stationary condition.

3. A duplicating machine wherein a plurality of record strips and at least one transfer ma-

terial strip of less width than that of the record strips are carried by free leading ends in continuous manner from separate supply sources in interleaving, superposed manner over a table, comprising record strip feeding means engaging the marginal side edge portions only of the record strips leaving the transfer strip free therebetween, said feeding means intermittently advancing the record strips in unison a predetermined distance across said table; means yieldingly holding said transfer strip under tension against travel induced by drag of said record strips therealong during said advancement; means realigning said record strips at the end of each operation of said record strip feeding means; and means operable in timed sequence with and during operation of said record strip feeding means prior to operation of said realigning means, momentarily compressing together said record and transfer strips and dragging said transfer strip along with the record strips against the resistance of said holding means an increment of the distance of said record strip advancement.

4. A duplicating machine wherein a plurality of record strips and at least one transfer material strip of less width than that of the record strips are carried by free leading ends in continuous manner from separate supply sources in interleaving, superposed manner over a table, comprising record strip feeding means engaging the marginal side edge portions only of the record strips leaving the transfer strip free therebetween, said feeding means intermittently advancing the record strips in unison a predetermined distance across said table; means yieldingly holding said transfer strip under tension against travel induced by drag of said record strips therealong during said advancement; means realigning said record strips at the end of each operation of said record strip feeding means; and means operable in timed sequence with and during operation of said record strip feeding means prior to operation of said realigning means, momentarily compressing together said record and transfer strips and dragging said transfer strip along with the record strips against the resistance of said holding means an increment of the distance of said record strip advancement; said machine having a tape carried transversely across said table under said transfer strip; means operating said record strip feeding means in successive increments of said predetermined distance; tape feeding means operating to feed the tape across the table; said tape feeding means being actuated by said record strip increment feeding means feeding the tape a distance at least equal to the width of said record strips.

5. A duplicating machine wherein a plurality of record strips and at least one transfer material strip, all having free leading ends, are carried in interleaved, superposed relation from individual supply sources over a table, and a tape is carried across the table under said transfer strip in a transverse direction relative to the strip travel, the combination of record strip feeding means normally advancing said record strips only across the table a predetermined distance, said feeding means engaging the marginal side edges only of said record strips during said advancement leaving said transfer strip free of engagement between said edges; means yieldingly holding said transfer strip against advancement with said record strips due to frictional drag of the record strips thereover, said holding means being

located at said transfer material supply source maintaining said transfer strip under longitudinal tension between said material source and its free end; means aligning said record sheets at the end of said advancement and setting up positive engagement between said record strip feeding means and the record sheets for a successive starting feeding of those strips; and means compressively holding said transfer strip against said record sheets momentarily operated by said record strip feeding means prior to operation of said aligning and starting means; said transfer strip holding means yielding to permit a degree of advancement of the transfer strip, wherein the degree is but an increment of the overall said record strip advancement.

6. A duplicating machine wherein a plurality of record strips and at least one transfer material strip, all having free leading ends, are carried in interleaved, superposed relation from individual supply sources over a table, and a tape is carried across the table under said transfer strip in a transverse direction relative to the strip travel, the combination of record strip feeding means normally advancing said record strips only across the table a predetermined distance, said feeding means engaging the marginal side edges only of said record strips during said advancement leaving said transfer strip free of engagement between said edges; means yieldingly holding said transfer strip against advancement with said record strips due to frictional drag of the record strips thereover, said holding means being located at said transfer material supply source maintaining said transfer strip under longitudinal tension between said material source and its free end; means aligning said record sheets at the end of said advancement and setting up positive engagement between said record strip feeding means and the record sheets for a successive starting feeding of those strips; and means compressively holding said transfer strip against said record sheets momentarily operated by said record strip feeding means prior to operation of said aligning and starting means; said transfer strip holding means yielding to permit a degree of advancement of the transfer strip, wherein the degree is but an increment of the overall said record strip advancement; and means operable in conjunction with said record strip feeding means, advancing said tape transversely across the record strips.

7. A duplicating machine wherein a plurality of record strips and at least one transfer material strip, all having free leading ends, are carried in interleaved, superposed relation from individual supply sources over a table, and a tape is carried across the table under said transfer strip in a transverse direction relative to the strip travel, the combination of record strip feeding means normally advancing said record strips only across the table a predetermined distance, said feeding means engaging the marginal side edges only of said record strips during said advancement leaving said transfer strip free of engagement between said edges; means yieldingly holding said transfer strip against advancement with said record strips due to frictional drag of the record strips thereover, said holding means being located at said transfer material supply source maintaining said transfer strip under longitudinal tension between said material source and its free end; means aligning said record sheets at the end of said advancement and setting up positive engagement between said record strip feed-

ing means and the record sheets for a successive starting feeding of those strips; and means compressively holding said transfer strip against said record sheets momentarily operated by said record strip feeding means prior to operation of said aligning and starting means; said transfer strip holding means yielding to permit a degree of advancement of the transfer strip, wherein the degree is but an increment of the overall said record strip advancement; and means operable in conjunction with said record strip feeding means, advancing said tape transversely across the record strips; said tape advancing means simultaneously operating said record strip feeding means an increment only of the total of said predetermined distance, for each tape advancement of the width of the record strips.

8. A duplicating machine wherein a plurality of record strips and at least one transfer material strip, all having free leading ends, are carried in interleaved, superposed relation from individual supply sources over a table, and a tape is carried across the table under said transfer strip in a transverse direction relative to the strip travel, the combination of record strip feeding means normally advancing said record strips only across the table a predetermined distance, said feeding means engaging the marginal side edges only of said record strips during said advancement leaving said transfer strip free of engagement between said edges; means yieldingly holding said transfer strip against advancement with said record strips due to frictional drag of the record strips thereover, said holding means being located at said transfer material supply source maintaining said transfer strip under longitudinal tension between said material source and its free end; means aligning said record sheets at the end of said advancement and setting up positive engagement between said record strips feeding means and the record sheets for a successive starting feeding of those strips; and means compressively holding said transfer strip against said record sheets momentarily operated by said record strip feeding means prior to operation of said aligning and starting means; said transfer strip holding means yielding to permit a degree of advancement of the transfer strip, wherein the degree is but an increment of the overall said record strip advancement; and means operable in conjunction with said record strip feeding means, advancing said tape transversely across the record strips; said tape advancing means simultaneously operating said record strip feeding means an increment only of the total of said predetermined distance, for each tape advancement of the width of the record strips; and means actuated by said tape advancing means clipping off the tape portion advanced beyond the side edges of the record strips.

9. In a duplicating machine wherein a plurality of record sheets are directed in superposed relation one way by free leading ends from a supply source across a table, a plurality of transfer material sheets are interleaved between said record sheets directed by free ends therebetween of continuous strips leading from a supply source one of said transfer material sheets being under the lowermost of the record sheets, and a tape directed across the table under said one transfer sheet and transversely thereof, means advancing the record sheets a predetermined distance; means normally holding said transfer sheets during said record sheet advancement; means interengaging the transfer sheets with said record

11

sheets momentarily during said record sheet advancement for advancement of the transfer sheets an increment of said predetermined distance, and means advancing said tape across said table during said record sheet increment 5 advancement.

EDGAR M. McNABE.
